UNITED STATES PATENT OFFICE.

CHARLES F. HAASE, OF EAST ATCHISON, MISSOURI.

SHADE AND CURTAIN HOLDER.

1,021,596.

Specification of Letters Patent. Patented Mar. 26, 1912.

Application filed May 31, 1911. Serial No. 630,305.

To all whom it may concern:

Be it known that I, CHARLES F. HAASE, a citizen of the United States, residing at East Atchison, in the county of Buchanan 5 and State of Missouri, have invented new and useful Improvements in Shade and Curtain Holders, of which the following is a specification.

The object of the invention is to facilitate 10 the adjusting of fixtures for shades and the like to the different lengths of rollers, and the connecting of these devices to a window casing.

Other objects will appear and be better 15 understood from the following description taken in connection with the accompanying drawings, in which,

Figure 1 is front elevation of the device applied to a window casing. Fig. 2 20 is a detail perspective of one end portion of the device. Fig. 3 is an end elevation of the same. Fig. 4 is a plan view of the device.

The brackets *a* and *b* are arranged on 25 the opposite sides 5 and 6 of the window casing and are adapted to support the ordinary shade and curtain, the shade roller and the curtain pole being engaged by the brackets in a manner to be described presently. The brackets *a* and *b* are preferably 30 formed though not necessarily of metal and may be formed in any suitable manner such as by stamping the same from sheet metal, in which event the necessary bending required 35 in order to form the bracket to be presently described will be accomplished after the blank has been stamped from the sheet.

Since the brackets *a* and *b* are identical 40 in structure with the exception that they are formed right and left, a description of one will be sufficient for both:—Each bracket includes a bearing portion 6' which may be shaped to bear on the face of the 45 window casing or any other suitable portion thereof and at one end is formed with an angular-shaped tooth extension 7 the teeth 8 of which are arranged so as to be driven or otherwise forced into one side of the 50 window casing. A pole support 9 connects with the bearing portion 6' and is arranged at an angle thereto and has a vertical socket 10 to receive one end of a curtain pole or the like. One end portion of the bearing 55 plate 6' may be reduced if desired as shown at 11 and a suitable support formed by

bending the outer end of the portion 11 into an angular shape as shown at 12. The shade bracket 13 is herein shown as having a portion 14 provided with a clamping 60 means such as a screw 15 and winged nut 16, the former sliding in a guide slot 17 and cooperating with the nut to secure the bracket 13 at various distances from the support 12. The brackets 13 are formed with suitable openings 18 to receive the trunnions at the opposite end of the ordinary shade roller. For connecting the brackets and serving to additionally support the same I make use of a sectional tie rod, the sections 70 19 and 20 of which are herein shown as provided at one end with eyes 21 each of which receives the other section. The sections 19 and 20 extend through openings in the supports 12 and also through openings 75 in the shade brackets 13 serving to additionally support and guide the same, the end portions of said sections extending through the curtain brackets 9 and terminating in angular shape of reversely bent 80 sharpened end portions 22 which are adapted to extend around the remote edges of the window casing and bite into the same. A contractible clamping sleeve 23 receives the inner end portions of the sections 19 85 and 20 and is contracted therearound in any preferred manner such as through the co-operation of a screw 24 and winged nut 25.

In use the brackets *a* and *b* are adjusted 90 on the opposite sides 5 and 6 of the window casing and to the proper position above the floor, after which the toothed end portions are forced into the sides 5 and 6. The shade brackets are then adjusted to the 95 length of the shade roller after which they are secured as before described and the sharpened end portions 22 of the tie rod are next driven into the sides of the casing. When this has been done the sleeve 23 is 100 contracted so as to prevent endwise movement of the sections 19 and 20 whereupon the device is positioned to support either a shade or a curtain or both of these hangings.

Although I have shown and described one embodiment of the invention it is to be understood that I am not to be limited to the specific description of the same nor to the arrangement of the parts, since it will be 110 manifest that various changes may be made, in the scope of the appended claims with-

out departing from the spirit or sacrificing any of the advantages of the invention.

What I claim as new is:

1. In a fixture for shades, curtains and the like, the combination of a plurality of curtain pole brackets having toothed end portions to bite into the opposite sides of a window frame, an extensible tie rod connecting said brackets and having angular shaped sharpened portions also to bite into the opposite sides of a window frame and shade roller brackets adjustably secured to the curtain pole brackets.
2. In a fixture for shades, curtains and the like, the combination of a plurality of

curtain brackets having angular shaped sharpened end portions to bite into the opposite sides of a window frame, an extensible tie rod connecting said brackets and having angular shaped sharpened end portions adapted to engage with the opposite sides of the window casing, and shade brackets adjustably secured to the curtain brackets and slidably fitted on the tie rod. 20

In testimony whereof I affix my signature in presence of two witnesses.

CHARLES F. HAASE.
